UNITED STATES PATENT OFFICE.

JOHN H. HAYDEN, OF PELHAM MANOR, NEW YORK.

STABILIZED PROJECTILE.

1,181,136.

Specification of Letters Patent. Patented May 2, 1916.

Application filed February 26, 1915. Serial No. 10,677.

To all whom it may concern:

Be it known that I, JOHN H. HAYDEN, a citizen of the United States of America, and a resident of Pelham Manor, county of 5 Westchester, State of New York, have invented certain new and useful Improvements in Stabilized Projectiles, of which the following is a specification.

My invention relates to ordnance, and 0 particularly to stabilizing projectiles against tumbling in a vertical plane and deviation from their line of flight.

It has been suggested to provide helical rifling bands within a gun barrel with which 5 a projectile cooperates during its passage through the gun, in order that a rotation about its longitudinal axis may be imparted to the projectile as it starts on its flight, and whereby it may possess some of the properties of the gyroscope.

The manufacture of guns is very expensive, and the item of the cost of cutting the grooves within the barrel to provide the lands of the rifling is largely the cause of 25 the high total cost of manufacture. Furthermore, the necessity for the presence of the rifling bands within the rifle limits its useful life to a few more than a hundred shots, because every projectile in its passage tears away a part of the lands and the rifling disappears. This is true regardless 30 of the efforts to perfect the design and the precision of manufacture without regard to increase of total cost. In other words, it 35 is impossible to make a long-lived rifle at any cost.

The cost of a gun is greatly increased by the necessity of so designing its long barrel and its carriage that the severe torsional 40 stresses set up in the barrel as it imparts rotation to the projectile will not tear off the end of the barrel nor tear the barrel bodily from its support. The severity of the torsional stresses and the magnitude of 45 the problem of designing a gun and its mounting to withstand them are readily apparent when one realizes that from 25% to more than 50% of the force of the powder charge is expended in imparting rotation 50 to the projectile through the medium of rifling bands. This waste of force of the powder increases much more rapidly than the range, thereby absolutely limiting the range of the rifle. Furthermore, the caliber 55 and range of a rifle are limited, because it is impossible to provide a metal band on

a very large projectile which will take and hold the lands without stripping as the projectile passes through the gun.

To sum up, the method of imparting rotation to the projectile by the use of rifling bands results in high cost of manufacture of gun and carriage in the providing of rifling bands and designing and mounting the barrel to withstand torsional stress, and a short 60 life of the piece due to erosion of the bands and of the explosion chamber by the powder, in the inefficient use of the force generated by the powder charge which limits the range and in the limitation of the range and caliber 65 of the gun, particularly when the total weight is limited, as on ships.

The object of my invention is to provide a projectile with a stabilizing means, so that it will not have to be rotated as a whole, 70 and the rifling within a gun, along with all its disadvantages and limiting factors, may be dispensed with and a long-lived large or small caliber smooth-bore gun may be made and mounted at a cost considerably less than 75 the cost of making and mounting a rifle, and in such a gun the full explosive force of the powder may be used as projecting force. To this end, I mount a stabilizing wheel 80 within a projectile, and provide means for 85 imparting rotation to the stabilizing wheel before the projectile starts on its flight and even after it is within the gun, and arrange the operating means for the stabilizing wheel so that it may be controlled, as 90 to its actuation or as to the release of power stored up within it, from without the projectile. The stabilizing device is designed 95 to afford the same stabilizing effect as the rotation of the projectile, and, being within the projectile and properly positioned, the air pressure has no opportunity to retard it and decrease its effect, and it is more efficient due to the possibility of locating it in the projectile so that its stabilizing effect 100 may be most efficiently taken advantage of. After the projectile has proceeded in its flight for a certain distance, its axis is at an angle vertically with the actual line of flight, and the air pressure is greater on the bottom 105 of the front face of the shell. This tends to cause the shell to tumble, and, in addition, the rotation of that part of the shell which is in contact with the denser air on the one face of the shell causes an increase in the amount of "drift" which the shell has due to other causes. In a projec- 110

tile embodying my invention, this increase of drift is avoided, because the shell itself is not rotating. It is, therefore, seen that by the use of my invention great economy 5 of installation and operation of a gun is obtained, with greater accuracy of operation and without the limitations of range and caliber imposed by the inadequacy of the method of stabilizing projectiles by the use 10 of rifling.

Further objects and advantages of my invention will appear from the following detailed description when taken in connection with the accompanying drawings forming a 15 part of this specification and in which:—

Figure 1 is a sectional view of a gun, showing a projectile therein, partly broken away to show a stabilizing wheel mounted within the projectile in accordance with my 20 invention; Fig. 2 is a sectional view of the projectile shown in Fig. 1; Fig. 3 is a partial sectional view of the stabilizing wheel and its operating mechanism, as shown in Figs. 2 and 7; Fig. 4 is a sectional view on the line 25 4—4 of Fig. 3; Fig. 5 is a partial section on the line 5—5 of Fig. 3; Fig. 6 is a sectional view of a gun, showing a modified form of projectile and powder casing therein; Fig. 7 is a sectional view of the projectile and its 30 powder casing shown in Fig. 6; Fig. 8 is a sectional view on line 8—8 of Fig. 7; Fig. 9 is a sectional view on line 9—9 of Fig. 7; and Fig. 10 is a rear view of the projectile shown in Fig. 2.

35 In large caliber guns, the common type of projectile comprises a hollow shell containing explosive, which is ignited by a percussion cap when the projectile strikes, and in Fig. 1 this projectile is shown positioned 40 within the barrel 2 of a smooth-bore gun, which has a powder chamber 3 behind the projectile 1, which is closed by the breech block 4 in the ordinary manner. The powder, which is placed within the chamber 3 45 in the usual manner, is ignited in any known way to provide a projecting force for the projectile. The projectile 1 comprises a shell having a chamber 5 closed at the back by a wall 6 which is screwed into the shell. 50 In this wall is screwed the ordinary percussion fuse 7 of the type above described. Within the chamber 5 there is mounted a stabilizing wheel 8 and its operating mechanism M, which may be of the spring motor 55 type or any other type of motor which may be practically inclosed within this confined space and which may be employed to impart rotation to the stabilizing wheel 8 at a pre-determined time. The stabilizing wheel 8 60 is mounted upon an axle 9, whose axis substantially coincides with the axis of the projectile, and which is mounted in roller bearings 10 and provided with a thrust bearing 11, so that it is given a forward 65 velocity along with the projectile. Mounted

on the hub of the stabilizing wheel is a gear 12, which meshes with an overrunning gear 13, which comprises a gear ring 14 and a disk 15 connected together by an ordinary over-running clutch 16. The disk 15 is 70 driven by the shaft 17, which receives its rotation from the operating mechanism M. It is thus seen that a great turning effort may be imparted to the stabilizing wheel for a short time, and when the power producing 75 the turning effort is exhausted the driving mechanism will overrun and the stabilizing wheel will not be retarded. It is intended in this case that the driving mechanism shall comprise an energy-storing device of any 80 known type, for example, a spring motor, and, in order that this energy may be released to impart a rotation to the shaft 17 at the desired time, so that the stabilizing wheel may have its maximum speed when 85 the projectile starts on its flight, a trigger mechanism is provided to release the stored energy. The trigger mechanism comprises a shaft 18 driven by the operating mechanism, which shaft has mounted on it a gear 19, 90 which meshes with the gear 20 mounted upon shaft 21. On the shaft 21 there is also mounted a ratchet wheel 22, with which co-operates a ratchet or locking dog 23 mounted on a pivot 24 and held in place 95 thereon by friction, so that, when moved out of contact with the ratchet tooth 22', it will stay in that position, which results in the releasing of the ratchet tooth 22'. The ratchet or dog 23 co-operates with the ratchet 100 tooth 22' on the ratchet wheel, and, in order to disengage it therefrom, a conical head 24 is provided on the operating rod 25, and the operating head is so positioned relatively to the ratchet or dog that an axial movement thereof will swing the ratchet or dog 23 about its pivot 24 to disengage it from the ratchet tooth 22'. 105

By the mechanism just described a great amount of energy may be released by a very 110 small pressure, since the ratchet wheel 22 is geared up from the driving shaft 18. The operating rod 25 passes through the chamber 5 and is surrounded by a tube 26 as it passes through said chamber to protect it 115 from the powder which is inclosed therein. The rod 25 passes through the wall 6 and projects therefrom. Secured at 27 on the wall 6 is a plate 28, which co-operates with the rod 25, so that a pressure on plate 28 120 will move the conical head 24 axially to move the ratchet or dog 23. When powder is put into the chamber 3 behind the projectile, it is forced home by the breech block or a ram, and it is intended that this final 125 forcing home of the powder shall press upon the plate 28 and release the operating mechanism M to impart rotation to the stabilizing wheel 8. In order that the plate 28 may not be prematurely pressed, a lock 29 130

is slid under it in the groove 30, and this lock 29 is removed just before the projectile is placed in its position in the gun.

In Fig. 6 there is shown a projectile 31 of a smaller caliber, positioned in the barrel 32 of a smooth-bore gun of corresponding caliber. The powder charge is contained in a metallic case 33, and the rear of the gun barrel is closed by the usual breech block 34. In the rear of the case 33 is fixed an ordinary percussion cap 35 for igniting the projecting charge within the case. The projectile 31 is of the shrapnel type, and has a typical time-fuse head 36 for igniting the bursting charge 37 and scattering the shrapnel balls 38. Within the rear of the shell, in this case, the operating mechanism M is mounted to drive the stabilizing wheel 8, and the operating mechanism M is released in the same manner as in the case of the large-caliber projectile above-described, except that the operating rod 25' is extended through the rear end of the case 33 and is protected by the tube 26' as it passes through the powder charge. Riveted on the rear of the case 33 is a plate 28', which co-operates with the end of the rod 25' to move it to release the operating mechanism, as above-described in connection with the large-caliber projectile. The plate 28' is locked from being swung to operate the rod 25' by a locking member 29', similar to the locking member 29 above-described. The plate 28', being on the rear of the powder case 33, is intended to be pressed down against the rear of the case by the breech block 34 when it is put in closed position and the case 33 forced home, so that, in this case, the stabilizing wheel is started just as soon as the breech block is closed.

While I have described my stabilizing device in detail and as comprising a stabilizing wheel driven by a motor device, the motor device in the embodiment described being contained within the projectile itself and the energy stored therein being released by a releasing mechanism operated by a rod which is operated by forcing home the powder charge and closing the breech block, I do not intend to limit myself to this specific construction.

I intend that my invention shall be limited only by the claims hereunto appended, and that I shall not be limited to that embodiment of my invention wherein the operating mechanism and the releasing mechanism for the energy therein stored are positioned as specifically described.

I intend that my invention shall be considered as broadly defined by the claims and that I may be permitted to impart rotation to the stabilizing wheel by any means which will come within the scope of my invention as defined by the claims.

I do not intend that I shall be confined to

any particular energy-storing or energy-producing or imparting means, but that I shall be entitled to any such means as come within the scope of the appended claims.

What I claim and desire to secure by Letters Patent of the United States is as follows:—

1. In combination with a gun for projecting a projectile through the air, an aerial projectile having a stabilizing wheel and means operative independently of the projectile-propelling force for actuating said stabilizing wheel.

2. In combination with a gun for projecting a projectile through the air, an aerial projectile having a stabilizing wheel, means operative independently of the projectile propelling force for actuating said stabilizing wheel, and means for setting said actuating means into operation.

3. In combination with a gun for projecting a projectile through the air, an aerial projectile having a stabilizing wheel, and means entirely inclosed within said projectile and operative independently of the projectile propelling force for actuating said stabilizing wheel.

4. In combination with a gun for projecting a projectile through the air, an aerial projectile having a stabilizing wheel, and means comprising an energy storing device and operative independently of the projectile propelling force for actuating said stabilizing wheel.

5. In combination with a gun for projecting a projectile through the air, an aerial projectile having a stabilizing means, means comprising an energy storing device and operative independently of the projectile propelling force for actuating said stabilizing means, and means for releasing the stored energy from without said projectile.

6. In combination with a gun for projecting a projectile through the air, an aerial projectile having a stabilizing means, a motor therefor operative independently of the force applied to said projectile to move it longitudinally, and means for putting said motor in operation from without said projectile.

7. In combination with a gun for projecting a projectile through the air, an aerial projectile adapted to be propelled through the air by an explosion within said gun, said projectile being provided with a stabilizing wheel and means operative independently of the projectile-propelling force for actuating said stabilizing wheel.

8. In combination, an aerial projectile having a stabilizing wheel therein, means for imparting rotation to said wheel, and means operative independently of said last named means and including a gun for projecting said projectile through the air by the action of an explosion within the gun.

9. The combination with a gun, of a projectile adapted to be propelled wholly by explosion within said gun and outside of the projectile, a stabilizing wheel within said projectile, and means for rotating said wheel, said last named means and said stabilizing wheel being arranged to act independently of force applied to said projectile to move it longitudinally and to produce no longitudinal force. 60
10. In combination, an aerial projectile, and stabilizing means including operating means therefor comprising an energy-storing device both entirely inclosed within said projectile and means for releasing the energy stored therein. 65
11. In combination, an aerial projectile, and stabilizing means including operating means therefor and entirely inclosed within said projectile, said operating means comprising an energy-storing device and means for releasing the stored energy from without said projectile. 70
12. In combination, a projectile for a breach-loading gun, a stabilizing means and operating means therefor and within said projectile, said operating means comprising an energy-storing device and means for releasing the stored energy upon closing the breech of the gun. 75
13. In combination, a gun having a removable breech block, a projectile therefor having within it a stabilizing means, and means for putting said stabilizing means into operative condition upon replacing said breech block. 80
14. In combination, an aerial projectile, and stabilizing means including operating means therefor comprising an energy-storing device and a connection between said stabilizing means and energy-storing device which permits said stabilizing means to overrun said operating means when the energy is exhausted, said stabilizing means and energy-storing device being entirely inclosed within said projectile, and means for releasing said stored energy from without said projectile. 85
15. The combination with a gun having a breech block, of a projectile therein, said projectile having a stabilizing device within and means for putting the stabilizing device into operative condition while the projectile is in position in the gun, said means extending through the explosion chamber and cooperating with the breech block. 90
16. In combination, an aerial projectile for a breach-loading gun, a stabilizing means, an operating means therefor, means for setting said operating means in motion, said last-named means being adapted to be actuated on ramming home the powder charge. 95
17. In combination, a projectile, a stabilizing means therefor, operating means for said stabilizing means, a member extending through the rear of the projectile for setting said operating means in motion, a member mounted for motion with respect to the projectile and coöperating with said first-named member. 100
18. In combination, a projectile, a stabilizing device therefor, operating means for said stabilizing device, a powder casing for said projectile and a member extending through said casing for setting said operating means in motion and adapted to be actuated from without said casing. 105
19. In combination with a gun for projecting a projectile through the air, an aerial projectile adapted to be propelled through the air by an explosion within said gun, said projectile being provided with a stabilizing device comprising a stabilizing wheel and means operative independently of the projectile-propelling force for actuating the said stabilizing wheel. 110
20. In combination with a gun for projecting a projectile through the air, an aerial projectile having a stabilizing means entirely inclosed therein, and means operative independently of the projectile propelling force for actuating said stabilizing means. 115
21. In combination with a breech-loading gun for projecting a projectile through the air, an aerial projectile having a stabilizing wheel, means operative independently of the projectile propelling force for actuating said stabilizing wheel, and means for setting said actuating means into operation upon the closing of the breech of the gun. 120
22. In combination with a gun for projecting a projectile through the air, an aerial projectile adapted to be propelled through the air by the action of an explosion within said gun and having a stabilizing wheel, and a motor for said wheel operative independently of the force applied to said projectile to move it longitudinally. 125
- In testimony whereof, I have signed my name to this specification, in the presence of two subscribing witnesses.
